UNITED STATES PATENT OFFICE.

JOSEPH A. STEINMETZ, OF PHILADELPHIA, PENNSYLVANIA.

OFFENSIVE DEVICE CARRIED BY AIRCRAFT.

1,136,494.

Specification of Letters Patent. Patented Apr. 20, 1915.

Application filed April 30, 1914. Serial No. 835,453.

To all whom it may concern:

Be it known that I, JOSEPH A. STEINMETZ, a citizen of the United States, residing at Philadelphia, in the county of Philadelphia 5 and State of Pennsylvania, have invented certain new and useful Improvements in Offensive Devices Carried by Aircraft, of which the following is a specification, reference being had therein to the accompanying drawing.

The general object of this invention is to provide for suspending bombs from aircraft and exploding them in more or less close proximity to points of attack, the aircraft 15 being meantime at a safe distance from the point of explosion and preferably beyond the reach of accurate gun fire.

The bombs employed vary in character according to the special object in view, sometimes containing high explosives only, sometimes being incendiary or adapted to scatter firebrands among ammunition supplies, gasolene stores, etc., and sometimes large shells adapted to project fragments, grape, 25 or the like over a large area.

In the accompanying drawings, Figure 1 shows in elevation an airship provided with my devices. Fig. 2 is an enlarged view of a common form of bomb sometimes employed.

In these figures, A represents any suitable aircraft, shown in this instance as a balloon of the dirigible type, provided with any desired form of hand or power operated reel B, carrying a great length of wire C. The air craft being at any desired height, a bomb D provided with an exploding device F is attached to the free end of the wire and lowered into the zone where 35 destructive explosion is desired. This bomb as shown in Fig. 2 is of a kind in common use, explosion being caused by a pull upon a loop F', and to this loop is secured a rigid rod F² which forms above the bomb

45 a loose loop encircling the suspending wire. Upon the wire at the aircraft is placed a loosely sliding weight E, and this being released by the aviator at the proper time slides rapidly down the wire which, whether 50 vertical or inclined, guides it to the bomb. When it reaches and depresses the rod F²

explosion is caused. A grapple G may when desired be attached to the loop F' or the rod F² in such manner that if the grapple engages any strongly resisting body, on the 55 earth or in the air, an explosion will be caused automatically. Usually, several bombs, exploding weights, and grapples will be carried, so that after one explosion the unused wire may be drawn up and the entire 60 operation be repeated.

The devices described may be used effectively and with little danger to the user if the airship be at great height in full daylight and at a much less height at night or 65 in a thick fog when search lights, small arms, or artillery are of practically no avail for defense against the use of my apparatus. It is also to be noted that high explosives create "air pockets" and "vortices" which 70 bring down aeroplanes which are beyond the radius of direct destructive effect, so that it is by no means necessary to produce explosion when the bomb is in close proximity to the craft to be destroyed. 75

Aside from actual destruction caused, the psychological effect of an aerial attack against which there is no defense is highly important. For example, the explosion of large shells above a body of troops by this 80 means is far more demoralizing than the explosion of like shells from a battery in a fixed and known location. The provision of both automatic and non-automatic means for causing the explosions is of moment 85 since it affords not only a double assurance of explosion but adapts the same devices to be used for one or another purpose at a moment's notice, now grappling a ship or building, for example, now exploding a 90 bomb above a body of troops where the use of the grapple is not desired and where the bomb is most effective when at a considerable height.

What I claim is:

1. The combination with a suitable aircraft in flight, of a bomb suspended therefrom by a flexible connection, and a grapple supported also by said connection and arranged to explode the bomb upon its own 100 engagement with any strongly resisting object.

2. The combination with a suitable aircraft in flight, of a bomb suspended therefrom by a flexible connection, grappling device arranged to explode the bomb when itself engaged with any strongly resisting body, and a bomb-exploding weight releasable at will at said aircraft and adapted to slide upon and be guided to the bomb by

said connection while descending by gravity.

In testimony whereof I affix my signature in presence of two witnesses.

JOSEPH A. STEINMETZ.
